UNITED STATES PATENT OFFICE.

FREDERICK HACHMANN, OF ST. LOUIS, MISSOURI, ASSIGNOR, BY DIRECT AND MESNE ASSIGNMENTS, OF THREE-EIGHTHS TO DAVID M. HUTCHINSON, OF FERGUSON, MISSOURI, ONE-SIXTEENTH TO CHAUNCEY R. WATSON, ONE-SIXTEENTH TO PHILIP E. MOODY, ONE-SIXTEENTH TO ELIJAH E. FRASER, ALL OF DETROIT, MICHIGAN, AND ONE-FOURTH TO HERMAN C. STIFEL, OF ST. LOUIS, MISSOURI.

SPARK-PLUG.

1,361,326.

Specification of Letters Patent.

Patented Dec. 7, 1920.

Application filed April 11, 1919. Serial No. 289,238.

To all whom it may concern:

Be it known that I, FREDERICK HACHMANN, a citizen of the United States, and resident of the city of St. Louis and State of Missouri, have invented certain new and useful Improvements in Spark-Plugs, of which the following is a specification containing a full, clear, and exact description, reference being had to accompanying drawings, forming a part thereof.

This invention relates to spark plugs and has for its primary object a spark plug having an auxiliary spark gap which is inclosed in a sealed chamber, thus intensifying the spark, the air in this chamber becoming highly electrified and acting as a storage for the electric current.

A further object is to construct a spark plug, the upper portion of which is dipped in insulating material and then baked so that, in case of moisture, there will be no short circuit of the plug.

Another object is to construct a spark plug wherein the grounded terminal or electrode extends almost completely around the casing, thereby making a much better connection between the casing and the grounded electrode than is possible in the spark plugs of the present construction.

30 In the drawings:

Figure 1 is a side elevation of my device.

Fig. 2 is a vertical cross sectional view of the same.

Fig. 3 is a bottom plan view.

35 Fig. 4 is a top plan view of the upper insulating section.

Fig. 5 is a bottom plan view of the same.

Fig. 6 is a top plan view of the lower insulating section, showing the groove formed 40 therein for the reception of additional insulating material.

Fig. 7 is a bottom plan view of the same.

Fig. 8 is a perspective view of the grounded electrode made use of.

45 Fig. 9 is an enlarged fragmental section, showing the method of securing the grounded electrode in the shell or casing.

Fig. 10 is a view of a modified form of my device.

50 Fig. 11 is a vertical cross sectional view of the same.

Fig. 12 is a top plan view of the water

shedding nut made use of in my modification.

Fig. 13 is a bottom plan view of Fig. 11, 55 and

Fig. 14 is a plan view of the modified grounded electrode.

Referring to the drawings 15 indicates a casing which is provided near its lower end 60 with screw threads 16, these screw threads being employed for securing the plug to the explosion chamber of an engine, the upper end being provided with faces 19 so as to allow the engagement of a wrench for screwing the body or casing 15 into the cylinder or explosion chamber. 65

The casing 15 is provided with a screw threaded bore 20 in which the packing or tightening nut 21 is inserted. The casing 70 15 is further provided with a bore 22 which bore is of less diameter than the bore 20, these bores 20 and 22, being concentric, form the shoulder 23. In this shoulder 23 is placed a washer or gasket 24 which is constructed of heat resisting and insulating material. On the washer 24 rests the flange 25 of the lower electrode carrying body 26. This body is constructed of porcelain, glass or any other non-conducting and heat 75 resisting material. 80

The flange 25 is provided with a semi-circular groove 27 in which a gasket 28 is placed, this gasket being of heat resisting and insulating material. The lower portion 85 of this carrying body is provided with a cylindrical bore 29 which extends only partially therein, as illustrated in Figs. 2 and 11. The upper portion of the body 26 is provided with a bore 30. Through this 90 bore, the electrode 31 passes and is cemented therein.

Surrounding the electrode 31 and extending above the flange 25, I provide a conical projection 32, the object of which is to provide an extended bearing or brace for the upper end of the electrode 31 and possibly confine the electrified air in the chamber 39 around the exposed end of said electrode. 95

Resting on the gasket 28, I provide a 100 member 33, this member being conical in shape and is provided on its lower end with a flange 34 which rests on the gasket 28.

On the upper edge of the flange 34 is

placed a washer or gasket 35 which is constructed of heat resisting and insulating material and on this washer or gasket, the end of the nut 21 rests, thus binding the members 26 and 33 securely together. On the member 33, I form a flange 36 on which is placed a washer 37, this washer being of any absorbent material so that, when the nut 29 is forced home, a water tight joint will be provided and prevent leakage of moisture within the plug.

The nut 21 is further provided with an extending flange 38. This flange is preferably circular in form and acts as a water shed, so as to prevent short circuiting of the plug in case moisture comes in contact with the plug.

The member 33 is provided with a conical cavity 39 which acts as a storage chamber and condenser for the primary spark. Within this chamber and extending through the member 33 is the electrode 40, this electrode being provided with a ball shaped terminal 41, which terminal is located in the cavity 39, the upper end being provided with screw threads 42 over which a binding nut 43 is located, this securing the electrode 40 in the member 33.

Over the upper end of the electrode is secured a binding post 44 which is provided with a knurled portion 45 and a plug 46 so that either a spring socket or a U-shaped terminal on the conductor wire can be made use of, when the plug is connected up.

The lower end of the casing 15 is provided with a groove 47 in which the grounded electrode 48 is seated, this electrode being provided with an extending portion 49, so as to create a gap between it and the electrode 31. In order to secure the electrode 48 within the groove 47, a flaring tool is made use of and the inner edge of the casing 15 flared as indicated by the numeral 50, so as to securely hold the electrode in place. By this means, I achieve a much better contact between the grounded electrode and the casing than is possible in structures of the present type or wherein a small hole is bored in the casing and a wire forced therein, this giving a connection at one point only; whereas my device practically extends entirely around the casing, eliminating the chance of the electrode loosening and dropping into the cylinder.

In the construction of my modification, the members 26 and 33 are constructed identical as shown in Fig. 2, but the nut 21 is placed below a water shedding flange 51, this flange being fully illustrated in Figs. 10, 11, 12 and 13 and is dipped into a bath of porcelain or other insulating material and extends beyond the faces formed on the casing 15, so that any moisture will drip clear of the faces 19.

The upper and lower faces of the water

shedding flange are inclined as indicated by the numerals 52 and 53 so as to prevent any moisture which may lodge thereon from running over the side face of the nut and cause a short circuit in the spark plug. 70

The end 54 of the electrode 36 is bent as indicated in Figs. 10, 11, 12 and 13 so as to form a spark gap between it and the electrode 55, this electrode being ring shaped and being crimped within the lower portion of the casing 15. This crimping means is accomplished by the same method as described previously. 75

The ring 55 is constructed of material which does not deteriorate by having the spark pass from it. In other words, the surface of the ring is not burned away, when the spark leaps the gap. This has been found to be a common failing where the casing itself was made use of as an 80 electrode.

As previously pointed out, the cavity 39 acts as a chamber for the electrified air caused by the primary spark. If it is found in practice that the electrified air in this 90 chamber becomes heated to such an extent that the elastic packing will not take care of the undue expansion, I may form a vent in the casing 15 adjacent the space or opening between the members 26 and 33. 95

Having fully described by invention, what I claim is:

1. A spark plug comprising a casing provided with an internal shoulder, a circular grounded electrode mounted in the lower end of said casing, an insulating member provided with a flange mounted in said casing, a gasket mounted in the casing and interposed between the shoulder formed in the casing and the flange on the insulating member, an electrode mounted in said insulating member and projecting above the upper end thereof, an upper insulating member provided on its lower end with a downwardly and outwardly flaring chamber, and having formed around its lower end a flange, and above said flange and spaced apart therefrom a second flange, gaskets mounted on the upper insulator and seated on each flange thereof, and a jam nut screw seated in said casing and provided with an outwardly projecting flange answering as a water shed. 105 110 115

2. A spark plug comprising a screw threaded casing, a ring-shaped electrode secured in the lower end thereof, a pair of insulating members located within the casing and spaced apart, a compressible gasket located between the insulating members, a fastening nut for securing said members within the casing, an outwardly extending flange formed integral with said nut and acting as a water shed, an electrode secured in each of said insulating members, and means located around one of the insu- 120 125 130

lators and within the nut for preventing the entrance of moisture into the interior of the plug.

3. A spark plug comprising a hollow screw threaded casing, a shoulder formed in said casing, a gasket located on said shoulder, an insulating member located within said casing, a flange formed around the upper end of said insulating member and resting on the gasket, a second gasket mounted on said flange opposite the first mentioned gasket, a second insulator provided with a downwardly flaring central opening resting on said second mentioned gasket, a pair of parallel spaced apart flanges formed around the outer surface of said second mentioned insulator, a packing

nut having a counterbore adapted to be screwed within the casing, a pair of gaskets mounted on the flanges and adapted to contact with the nut, the upper gasket and nut forming a water tight joint between the interior of the plug and the outside thereof, an electrode secured within each insulator and a projecting flange formed on the nut, 25 said flange adapted to act as a water shed.

In testimony whereof, I have signed my name to this specification, in presence of two subscribing witnesses.

FREDERICK HACHMANN.
